FRED MAIER, OF LOS ANGELES, CALIFORNIA, ASSIGNOR TO WESTERN VULCANIZER MANUFACTURING COMPANY, OF CHICAGO, ILLINOIS, A COPARTNERSHIP CONSISTING OF HERBERT K. WHEELOCK, FRANK A. WELLER, AND WALTER R. FONTAINE.

MATRIX FOR VULCANIZERS.

1,380,919.

Specification of Letters Patent. Patented June 7, 1921.

Application filed May 14, 1919. Serial No. 296,985.

To all whom it may concern:

Be it known that I, FRED MAIER, a citizen of the United States, residing at Los Angeles, in the county of Los Angeles and 5 State of California, have invented certain new and useful Improvements in Matrices for Vulcanizers, of which the following is a specification.

My invention relates to matrices for vul- 10 canizers, and refers particularly, although not exclusively, to matrices used in retreaders for tires where it is desired to make the retread with somewhat elaborate arbitrary designs thereon formed by suitable configu- 15 rations in the matrix.

In the art of vulcanizing as especially applied to retreading tires, a removable matrix, preferably made of aluminum or other readily heat-conducting and non-cor- 20 rosive metal, is often used in a mold of standard design, so that when it is desired to change the design of the article to be vul- canized, a new matrix may be substituted to accomplish this purpose.

25 In retreaders for tires, the vulcanizing bed is concave and of arcuate form to conform to the shape of the tire, a removable matrix being contained within this vulcanizing bed. The heat for the vulcanizing op- 30 eration is supplied by steam in a chamber adjacent to the walls of the vulcanizing bed or by other suitable heating means, so that the heat passes through the matrix and per- 35 forms the vulcanizing operation upon the tire.

It has proved very difficult and expensive to make a matrix having relatively complicated configurations thereon in order to give a correspondingly complicated design 40 to the tread of a tire. These designs are of such nature that it is exceedingly difficult to satisfactorily cast a matrix in finished form with all the surfaces of the configura- 45 tions free from blow-holes and other imper- fections.

It is the object of my invention to make a matrix having configurations thereon by a simple and relatively inexpensive process, which will greatly improve the finished 50 matrix.

In order that my invention may be more

readily understood, reference is made to the accompanying drawings, in which—

Figure 1 is a plan of a portion of a matrix showing the configurations thereon; and 55

Fig. 2 is a transverse section taken on the line 2—2 of Fig. 1.

In order to simplify the process of making the matrix indicated as a whole by 10, it is preferably made in the two longitudinally separated halves 11, which abut at their adjoining edges 12. The matrix as a whole is concave in cross section and longitudinally arcuate, so as to conform to the outside of the tire which is to be vulcanized. 65

The two halves 11, 11 of the matrix when first cast have a relatively plain inner surface. The configurations, such as 13 and 14 shown in the drawings, are preferably made of type metal or other similar metal having 70 a relatively low melting point, these configurations being provided with the lugs 15 extending into the beveled holes 16 in the matrix.

It will be observed that the holes 16 are 75 made with ends of least cross sectional area at the inner surface of the matrix, so that the lugs 15 which fill these holes serve to securely anchor the configurations 13 and 14 in position. The holes 16 preferably ex- 80 tend through the wall of the matrix, but, if desired, these holes may extend only from the inner surface of the matrix, terminating before they reach the outer convex surface thereof. 85

In the process of applying the configura- 90 tions, the holes 16 are first made in the matrix, which is preferably of aluminum or other similar heat-conducting and non-cor- 95 rosive metal, and a suitable mold for the configurations is then applied to the inner surface of the matrix. The type metal of which the configurations are formed is then poured into the mold either by directly pouring the same into the mold if the holes 16 do not extend to the outer surface of the matrix, or by pouring through the holes 16 if the latter extend entirely through the matrix wall. Upon solidification of the type metal forming the configurations, the 100 mold is removed and any projections from the castings are smoothed off. The mold may

be of any desired material such as is well known in the art; and the casting may either be formed under pressure or not, as desired. It is also within the discretion of the operator whether a single configuration or a plurality should be cast at the same time.

It will be apparent that by means of the process which I have described, the matrix is very quickly and easily supplied with configurations of any desired design, these configurations being very free from imperfections on account of the relatively small amount of metal which is cast at one time.

It will be apparent to those skilled in the art that many changes could be made in the details of the matrix which I have described, without departing from the spirit and scope of my invention.

What I claim is:

- 20 1. A matrix for vulcanizers, consisting of a main body portion having an anchoring surface thereon, and a configuration cast on to said body portion and engaging the said anchoring surface.
- 25 2. A matrix for vulcanizers, consisting of a main body portion and having an anchoring hole therein, and a configuration cast on said body portion and having a portion extending into said anchoring hole, whereby 30 the configuration is secured to said body portion.
- 35 3. A matrix for vulcanizers, consisting of a main body portion having a relatively plain surface and with a beveled anchoring hole extending into the wall of said matrix from said surface, and a configuration cast

on said surface and having a portion extending into said hole, whereby the configuration is securely fastened in position.

4. A matrix for vulcanizers, consisting of 40 a main body portion having a concave surface, a plurality of beveled anchoring holes extending into said matrix from said concave surface, and a plurality of configurations cast on said concave surface and having portions extending into said anchoring holes, whereby said configurations are securely fastened to said matrix.

5. A matrix for vulcanizers, comprising a metallic body portion having anchoring 50 holes extending inwardly from one surface thereof, and a plurality of metallic configurations cast on said matrix and having portions extending into said anchoring holes.

6. A matrix for vulcanizers, comprising 55 an aluminum body portion having an anchoring hole extending inwardly from one surface thereof, and a configuration of readily fusible metal cast on said surface and having a portion extending into said anchoring hole.

7. A matrix for tire retreaders, consisting of an aluminum body portion having a concave surface from which a beveled anchoring hole extends, and a type metal configuration cast on said concave surface and having a portion extending into said anchoring hole, whereby said configuration is securely fastened to said body portion.

Signed at Chicago, Illinois, this 5th day 70 of May, 1919.

FRED MAIER
